UNITED STATES PATENT OFFICE.

JOHN C. McLEAN, OF LAKEWOOD, OHIO.

DESIGN FOR A TIRE.

48,541.

Specification for Design.

Patented Feb. 8, 1916.

Application filed November 29, 1915. Serial No. 64,175. Term of patent 7 years.

To all whom it may concern:

Be it known that I, JOHN C. McLEAN, a citizen of the United States, residing at 1491 Waterbury road, in the city of Lakewood, county of Cuyahoga, and State of Ohio, United States of America, have invented a new, original, and ornamental Design for Tires, of which the following is a specification, reference being had to the accompanying drawings, forming a part thereof.

In said drawings, Figure 1 is a sectional view of my new design; and Fig. 2 is a top plan view of a portion of a tire showing my new design.

I claim:

The ornamental design for a tire, substantially as shown.

JOHN C. McLEAN.
